HIS ATTORNEY.

UNITED STATES PATENT OFFICE.

ALBERT VUILLEUMIER, OF BRISTOL, CONNECTICUT, ASSIGNOR TO THE NEW DEPARTURE MANUFACTURING COMPANY, OF BRISTOL, CONNECTICUT, A CORPORATION OF CONNECTICUT.

HEAT-TREATING APPARATUS.

Application filed May 7, 1927. Serial No. 189,618.

This invention relates to heat treating apparatus and comprises all the features of novelty herein disclosed, by way of example, in connection with a furnace for hardening 5 articles such as steel balls.

An object of the invention is to provide an improved hardening apparatus which will effect uniformity of heat treatment for all articles treated. Another object is to provide 10 an improved apparatus for handling articles for heat treatment and for economizing labor and heat.

To these ends and also to improve generally upon devices of the character indicated 15 the invention consists in the various matters hereinafter described and claimed.

The invention, in its broader aspects, is not necessarily limited to the specific features selected for mere illustrative purposes in the 20 accompanying drawings in which

Figure 1 is a vertical longitudinal section of a furnace.

Figure 2 is a transverse section, the right half of the figure being sectioned on line 25 A—A with loading chute omitted, and the left half of the figure being sectioned on line B—B of Figure 1.

Figure 3 is a section on line C—C of Figure 4, showing furnace tilting mechanism and 30 quenching apparatus.

Figure 4 is an end view of furnace tilting mechanism, the quenching apparatus being omitted.

Fig. 5 is an enlarged sectional view of certain parts of Fig. 1.

The numeral 2 indicates a furnace enclosed on all sides by steel plates and braced by angle irons 4 at the corners. Resting on the floor plates is an insulated, heat proof structure having a central heating chamber 6 for an article container and mixer, herein shown as a tumbling barrel or retort 8 which contains the articles, such as steel balls, to be heat treated. The barrel is internally provided 40 with inclined ribs or vanes 10 which mix the articles. The barrel has a contracted mouth 12 and is inclined when in heating position to retain the articles by gravity. The exterior of the small end of the barrel has a circular rail or track 14 resting on a pair of spaced supporting rollers 16. Each roller has trunnions 18 seated in inclined bearing notches in U-shaped blocks 20 having lateral

projections fitting in slots cut in vertical webs of an inverted channel iron 22. Beyond 55 the closed end of the barrel is an integral flange or extension 24 resting on spaced rollers 26 supported in a manner similar to the rollers 16. The flange 24 is braced by spokes or webs 28 which radiate from a hub 30 on 60 the closed end of the barrel. A driving sleeve 32 having projecting driving lugs 34 extending between the spokes or webs 28 is connected to and driven by a sleeve 36 carrying a sprocket wheel 38. The sleeve 36 is rotatably supported and held from endwise movement by ball bearings 40. The inner race ring of this ball bearing is held against a shoulder on the sleeve 36 by a nut 42 and the outer race ring is clamped against a shoulder 70 in a housing 44 by a cap 46. The spokes or webs 28 are held in driving relation to the lugs 34 by a headed rod 48 extending through the hub 30 and the sleeves 32 and 36 and pressed outwardly by a coil spring 50 interposed between the hub of the sprocket wheel 38 and nuts 52 on the end of the rod. The headed rod and the sleeves hold the tumbling barrel or mixer from axial movement. The clearance between the rod and the driving 75 sleeve 32 and the independent supports of the mixer and the sleeve allow the mixer to expand without impairing the driving connection. The housing 44 is supported by a bracket 54 on the end of the furnace. The 80 tube 32 is surrounded by heat insulating material 55. The sprocket wheel 38 is driven by a chain 56 from a sprocket wheel 58 on a shaft 60 driven by worm gearing in a 85 casing 62. The worm gearing is driven by an electric motor 64 supported with the casing 62 on the top of the furnace. The barrel is rotated slowly and continuously even when dumping its load. The barrel or mixer is of smaller size than the heating chamber 90 and is spaced from all of the walls thereof to allow access of heat to the sides and ends of the mixer. The chamber is entirely closed, the driving sleeve 32 being of such small diameter that it will carry away little heat 95 by conduction and it is not subject to much expansion and contraction due to variations in temperature in use and so it substantially fills its opening in the end wall. The opposite end of the mixer is always open to access 100 of heat, the inclination and contracted mouth 105

retaining the articles without requiring a cover.

Opposite the open end of the barrel is a door 66 having a frame lined with heat insulating and refractory material 67. A central opening in the door admits a loading chute 68 which extends into the open end of the barrel at a point above the bottom of the opening to leave a discharge space when the 10 furnace is tipped for dumping. The chute and the axis of the barrel or mixer are both inclined to the horizontal when the furnace is in normal position. The chute is closed by a removable plug 70 lined with heat insulating 15 material and having a wedging surface engaged by a locking lever 72 pivoted on the door and swingable up and down across the plug within the bend of a handle 74. In the chamber 6 and supported by ledges 76 and 78 20 formed by projecting bricks, are electric heating elements, herein shown as of the T-grid type, extending back and forth in horizontal and vertical series of courses 80 and 82. Extending through the top of the furnace is a 25 draft tube 84 which can be opened when desired to let in air for cleaning purposes. When the furnace is tipped to discharge its load from the barrel, the load drops through oval chute sections 86 and 88 set in heat insulating material 89 and leading down through 30 the bottom of the furnace to a discharge chute section 90. The discharge chute 90 enters a round perforated tube 92 and dips below the surface of quenching liquid in a deep, rec- 35 tangular tank 94 which surrounds the tube 92. Thus the charge is always wholly shielded from the atmosphere; the heating means is wholly independent of the tumbling barrel; only the work holding barrel rotates and 40 the work requires no traversing feed movement but is nevertheless thoroughly mixed by the vanes or ribs to insure uniformity of heat treatment. The lower end of tube 92 has a contracted mouth 96 to deliver quenched articles into buckets (not shown) of any suitable conveyor operated in the tank below a series of tubes 92 which receive charges from 45 a plurality of furnaces simultaneously.

The furnace 12 normally occupies the lower 50 inclined position indicated by dash lines in Figure 3 but can be tipped to the broken line position. Brackets 100, attached to the sides of the furnace, support it on a pivot shaft 102 which is journaled in brackets 104 attached 55 to an open frame 106 conveniently made by opposite channel irons 108 connected at the corners by angle plates 110. The frame rests on pedestals 112 at the sides of the tank 94 and the tube 92 is made large enough to allow 60 the movement of the furnace and chute 90 from the loading and operating position to the discharge position. Links 114 are pivotally connected to brackets 116 on the furnace by a shaft 118. The links are also 65 pivotally connected by pins 120 to gears 122

on a cross shaft 124 journaled in brackets 126 on a frame composed of connected I-beams 128 resting on risers or sills 130 on the floor 132. The gears are driven by pinions 134 on a cross shaft 136 journaled in the 70 brackets 126 and driven by worm gearing in a casing 138 resting on a channel iron frame 140. The worm gearing is driven by a motor 142 through a coupling 144. The lever 72 which locks the plug 70 is connected in any 75 suitable way to a switch (not shown) for starting any well known timing mechanism controlling the time of heat treatment. After a predetermined interval, the timing mechanism starts the motor 142 to dump the 80 articles, the motor stopping when the furnace returns to loading position. Subsequent movement of the locking lever 72, when removing and relocking the plug 70 after re-loading the barrel, again starts the timing 85 mechanism for a new cycle. Coupling the locking lever to the switch helps to insure charging of the furnace before starting the cycle. The heating chamber is surrounded by fire brick 150 outside of which are one or 90 more courses of heat insulating brick 152. The outermost courses 154 may be a cheaper grade of brick.

I claim:

1. In heat treating apparatus, a furnace 95 having a closed heating chamber, an article holding mixer rotatably mounted in the heating chamber and having an open mouth to facilitate access of heat to the interior and loading, the mouth of the mixer being contracted in size to retain articles by gravity; substantially as described.

2. In heat treating apparatus, a furnace having a closed heating chamber, an article holding mixer rotatably mounted in the heating chamber and having an open mouth to facilitate access of heat to the interior, and a loading chute extending through one end of the furnace into the open mouth of the mixer, the mouth of the mixer being contracted in size to retain articles by gravity and the loading chute being inclined when the furnace is in normal position; substantially as described.

3. In heat treating apparatus, a furnace 115 having a closed heating chamber, an article holding mixer rotatably mounted in the heating chamber and having an open mouth to facilitate access of heat to the interior, the axis of the mixer being normally inclined to the horizontal to receive articles and retain them by gravity; substantially as described.

4. In heat treating apparatus, a furnace having a closed heating chamber, an article holding mixer rotatably mounted in the heating chamber and having an open mouth to facilitate access of heat to the interior, a loading chute extending through one end of the furnace into the open mouth of the mixer, the mixer normally having its axis inclined 125 130

to the horizontal to receive articles from the chute and retain them by gravity; substantially as described.

5. In heat treating apparatus, a tiltable furnace having a closed heating chamber, an article holding mixer rotatably mounted in the heating chamber and having an open mouth to facilitate access of heat to the interior, a loading chute extending through one end of the furnace into the open mouth of the mixer at a point above the bottom of the opening, a discharge chute at the mouth of the mixer, means for tilting the furnace, the loading chute and the mixer normally having their axes at an inclination to the horizontal to receive articles by gravity and the tilting of the furnace enabling the articles to pass below the loading chute into the discharge chute; substantially as described.
- 20 6. In heat treating apparatus, a furnace having a closed heating chamber, an article holding mixer rotatably mounted in the heating chamber and having an open mouth to facilitate access of heat to the interior, the

mouth of the mixer being contracted in size 25 to retain articles, a loading chute extending through one end of the furnace into the open mouth of the mixer, and a removable plug for closing the chute; substantially as described.

- 30 7. In heat treating apparatus, a furnace having a closed heating chamber, an article holding mixer of smaller size than the chamber and spaced from all of the walls thereof to allow access of heat to the sides and ends 35 of the mixer, means in the heating chamber for rotatably supporting the mixer, driving means connected to one end of the mixer and extending through a wall of the heating chamber, the other end of the mixer being 40 constantly open to the chamber for access of heat and for loading and having a contracted mouth to retain articles; substantially as described.

In testimony whereof I hereunto affix my 45 signature.

ALBERT VUILLEUMIER.
